UNITED STATES PATENT OFFICE.

PATRICK H. HAUGH, OF SOUTH NORWALK, CONNECTICUT.

METHOD OF FORMING EDGES OF HAT-BODIES.

1,246,917.

Specification of Letters Patent. Patented Nov. 20, 1917.

Application filed August 11, 1917. Serial No. 185,682.

To all whom it may concern:

Be it known that I, PATRICK H. HAUGH, a citizen of the United States, residing at South Norwalk, county of Fairfield, State 5 of Connecticut, have invented an Improvement in Methods of Forming Edges of Hat-Bodies, of which the following is a specification.

This invention has for its object the production of hats with finished felted edges of 10 greatly increased thickness and alike on both sides, thus doing away with a raw edge or the finishing of a raw edge with a binding, and by making the thickened felted 15 edge of the brim alike on both sides, I enable the manufacturer to finish either side of a hat body and thus save as firsts, hat bodies having blemishes in one side which do not appear on the other side.

With these and other objects in view, I 20 have devised the novel method of forming the edges of hat bodies which I will now describe referring to the accompanying drawing, forming a part of this specification and 25 using reference characters to indicate the several parts.

Figure 1 is an elevation of a hat body after a hardening operation, and showing the manner in which a strip is cut from the 30 lower edge thereof;

Fig. 2 a similar view showing the manner in which the severed strip is attached, similarly to a binding, over the new edge of the body;

Fig. 3 a detail sectional view on an enlarged scale, showing the strip in place, the body being ready for the felting or sizing operations;

Fig. 4 a similar sectional view of a finished hat body, and

Fig. 5 is a perspective view of a completed hat having the edge of the brim finished in accordance with the present invention.

10 denotes a hardened hat body, 11 a strip 45 cut from the edge entirely around and 12 stitching by which the strip is attached in place over the new edge of the body.

In carrying out my novel method, the hat bodies are felted or hardened more or less 50 after removal from the cone so that they

may be handled without difficulty. As the edge of the body is now irregular and rough, a rounding operation is preferably performed to leave a straight edge. The operator then cuts off a strip entirely around 55 the body from one to one and one-half inches in width. This strip is then folded over the new edge of the body, so as to lie on both sides thereof and stitched in place as indicated in Fig. 2. The appearance of 60 the edge of the body with the severed strip folded over and stitched in place on the edge is indicated at the right in Fig. 2 and also in Fig. 3 which shows in section the edge ready for additional felting or sizing operations. 65 These additional felting or sizing operations may be performed in any ordinary or preferred manner, the only requirement being to size, shrink or felt the body down to 70 size. The result of these additional operations is to thoroughly incorporate the stitched on strip with the body, leaving the body with a rounded and smoothly finished edge of greatly increased thickness but 75 corresponding otherwise with the rest of the body and brim, and providing an edge greatly superior in every way and much neater and more attractive than either a cut edge or an edge finished by binding in the usual manner. During the operation of sizing or felting the bodies down to size, the 80 stitches are usually picked out. This completes the making of the body. The several operations required to complete the hat may 85 be performed in any ordinary or preferred manner and are not described as they form no portion of the present invention.

Having thus described my invention, I claim:

1. The method of forming the edges of 90 hat bodies which consists in cutting a strip from the edge of the body, folding the severed strip over the new edge of the body so that it lies on both sides thereof, stitching the strip in place, and then felting the body 95 down to size leaving it with a rounded felted edge of increased thickness.

2. The method of forming the edges of 100 hat bodies, which consists in hardening the body after removal from the cone, then

trimming the edge, then cutting a strip from the edge entirely around, then folding the severed strip over the new edge of the body, so that it lies on both sides thereof, then 5 stitching the strip in place, and then felting the body and stitched on edge down to size.

3. A hat body having a rounded felted edge of greater thickness than the body and alike on both sides, substantially as de- 10 scribed.

In testimony whereof I affix my signature.
PATRICK H. HAUGH.
